(57) **CLAIM**

The ornamental design for an overhead gunner protection kit, as shown and described.

DESCRIPTION

The invention described and claimed herein may be manufactured, used, and licensed by or for the U.S. Government for U.S. Government purposes.

FIG. 1 is a perspective view of an overhead gunner protection kit showing our new design;

FIG. 2 is a front elevation view thereof;

FIG. 3 is a left side elevation view thereof;

FIG. 4 is a right side elevation view thereof;

FIG. 5 is a rear elevation view thereof; and,

FIG. 6 is a top view thereof.

The bottom of the overhead gunner protection kit is not shown and forms no part of the claimed design.
